UNITED STATES PATENT OFFICE.

JAMES A. MOGLE, OF MISHAWAKA, INDIANA.

SHOEMAKER'S JACK.

1,134,889.

Specification of Letters Patent.

Patented Apr. 6, 1915.

Application filed July 20, 1910. Serial No. 572,815.

To all whom it may concern:

Be it known that I, JAMES A. MOGLE, a citizen of the United States, residing at Mishawaka, in the county of St. Joseph and State of Indiana, have invented certain new and useful Improvements in Shoemakers' Jacks, of which the following is a specification.

My invention relates to improvements in 10 shoemakers' jacks, and is especially adapted for quick repair work.

The object of the present invention is to provide a shoemaker's jack which permits the shoe last to be easily and quickly adjusted to varying positions, so as to render the part of the shoe to be worked upon more accessible.

Another object of the invention is to provide a shoemaker's jack which, while capable of many adjustments, is of simple and durable construction.

With these and other objects in view, the invention consists of certain novel features of construction as hereinafter described and 25 pointed out in the claims.

In the drawings employed for illustrating the embodiment of the invention:—Figure 1 is a side elevation thereof, showing one of its adjustments in dotted lines. Fig. 2 is a top view illustrating, by circular dotted lines, the rotary adjustments permissible of the shoe last and the jack standard independently of each other. Fig. 3 is a vertical sectional view through the center of the 30 jack base. Fig. 4 is a fragmentary view, partly in section, showing connection between the standard and swinging arm. Fig. 5 is a top view of one end of the swinging arm, and Fig. 6 is an edge view of a strap 35 tightening lever.

Referring now more particularly to the accompanying drawings, the reference character 10 represents a base member, having a vertical bore 11 through its center and a clamp screw 12 in the side thereof. The standard 13 has a reduced lower end 14, which passes downwardly into the bore of the base, and a shoulder 15 adapted to rest upon the base; or, as shown in the drawings, upon a washer or washers 16, interposed between the base and the shoulder for the purpose of adjusting the height of the jack to suit the workman. As mounted, the jack may be rotated on its base and the shoe last 40 adjusted to the desired position, the large dotted circle in Fig. 2 showing the sweep

of the last when a complete turn of the standard is made. The standard may be locked against rotation by manipulation of the clamp screw 12.

The upper end of the standard 13 terminates in a head 17, having spaced walls 18 between which one end of a swinging arm 19 is disposed, a pivot bolt 20 being passed through corresponding apertures in the arm and walls, and a nut 21 applied to the threaded end of the bolt, which latter has a hand wheel on the opposite end thereof, as indicated at 22. The end of the swinging arm is designed to snugly fit between the 65 walls of the head, but sufficiently loose so as to permit the arm to freely swing on its pivot, the close fit being desirable so that a slight drawing together of the walls by turning the pivot bolt will firmly clamp the 70 arm against movement. The arm is rounded on its lower edge, as at 23, so as to permit same to turn on its pivot without interfering with the bottom of the head, while the lower and end edges of the arm are adapted 75 to rest on the head bottom, and thus limit the movement or swing of the arm.

The free end of the swinging arm 19 is cylindrical in formation, and has ears 24 formed integral therewith and in parallel 80 relation, the cylindrical member, hereinafter referred to as the split head 25, being split its entire length and at a point between said ears. A screw bolt 26 engages threaded apertures in said ears for the purpose of 85 drawing the ears together and closing the split so as to effect a binding engagement between the head and the last supporting post 27, the lower end of which extends into the head. A screw 28 is inserted through 90 the head 25, the end thereof projecting into a circumferential groove 29 so as to hold the post against lengthwise movement and at the same time permit rotation thereof.

The post 27 is provided with a tapered 100 upper end and the shoe last 30 has a socket fitting over said tapered end. A lever 31 is pivoted to a ring 32, the latter being split and fitted into a shallow groove (not shown) in the post, and the ends connected by rivets 105 33. The ring may thus be turned in its seat, and the lever, which is used for drawing the strap 34 taut in order to hold the shoe upon the last, can be shifted to either the top or lower side of the last supporting post, when 110 in the position shown by dotted lines in Fig. 1. The endless strap 34 passes through an

opening 35, in the lever, and when the latter is pressed down against the post to tighten the strap over a shoe on the last, the end thereof will be over its pivotal center and the tension of the strap will hold same in place.

It will be seen from the foregoing description, that the shoe last and the jack standard are so mounted, that the former may be 10. turned or rotated while the latter remains stationary, and that the latter, or the jack as a whole may be bodily turned upon its base, the two independent movements or path of rotation being indicated by the large 15 and small dotted circles shown in Fig. 2. The last may also be swung so as to assume a vertical position, as shown in Fig. 1, and as the same may equally as well be rotated while in this position, it is evident that the 20 range of adjustments that may be made is such as to meet every requirement necessary to render every part of a shoe mounted thereon readily accessible, thus effecting a

saving of time and labor. The means permitting vertical adjustment of the jack, so 25 as to obtain the desired height for workmen of different stature, is also an important and desirable feature.

Having thus described my invention, what is claimed, is—

In a shoemaker's jack, the combination of a last-supporting post adapted to have a last mounted upon one end thereof, a ring rotatably mounted upon the post, an arm projecting radially from said ring, a clamping lever pivotally connected at one end with the outer end of the arm, and a last-clamping strap connected medially with the lever and adapted to pass around a last mounted upon the post.

In testimony whereof I affix my signature, in presence of two witnesses.

JAMES A. MOGLE.
